UNITED STATES PATENT OFFICE.

CHARLES E. EGAN, OF COLUMBUS, OHIO, ASSIGNOR TO THE EGAN ELECTRIC AND TELEPHONE MANUFACTURING COMPANY, OF PETERSBURG, ILLINOIS, A CORPORATION OF ILLINOIS.

SIGNAL-BELL FOR TELEPHONE SYSTEMS.

No. 818,673.

Specification of Letters Patent.

Patented April 24, 1906.

Application filed February 27, 1903. Renewed September 21, 1905. Serial No. 279,506.

To all whom it may concern:

Be it known that I, CHARLES E. EGAN, a citizen of the United States, residing at Columbus, in the county of Franklin and State 5 of Ohio, have invented certain new and useful Improvements in Signal-Bells for Telephones, of which the following is a specification.

My invention relates to call or signal bells 10 for telephone systems and the like, and has for its object to provide a combined ringer and condenser for use on signal and telephone lines employing alternating and direct currents.

15 To this end the invention comprises a call or signal bell provided with a polarized ringer with a magnet-coil on one leg thereof and a condenser on the other, so related that the ringing-circuit passes through said coil to the 20 condenser, the armature being first attracted by the core piece or leg of the coil and then upon the discharge of the condenser swinging over the other pole-piece and reestablishing the initial condition.

25 In systems of telephony wherein alternating currents are employed for signaling purposes and direct or battery currents are used upon the line it is necessary to employ a condenser of relatively large size and capacity in 30 series with each ringer-magnet to close the ringer-circuit. By means of my invention I provide a condenser that is applied to its intended use without providing any other connections and housing than those required for

35 the ordinary ringer-circuit and that affords a unitary instrument performing the functions of the two corresponding separate instruments in a more efficient manner and with a less expenditure of energy.

40 The invention is illustrated in the accompanying drawings, in which—

Figure 1 is a perspective view of the ringer-magnet and condenser with their circuit attachments. Fig. 2 is a plan view thereof. 45 Figs. 3 and 4 are a side elevation and an end view, respectively, of the apparatus; and Fig. 5 is a diagrammatic view showing the relation of the various parts including the circuits.

50 Referring to the drawings, *a* indicates an electromagnet-coil which is mounted upon one leg *c* of the usual type of horseshoe-core, which latter comprises a similar parallel leg

c', joined to the leg *c* by a back bar or supporting member *c*², which in turn is adapted 55 to be attached within the bell-box by perforated lugs *c*⁶. Midway between legs *c* and *c'* there is a metallic bar *c*³ adjustably attached to the back bar *c*² and carrying at its outer end a bracket *c*⁴ in which the armature *e* is 60 pivoted, so that the latter may vibrate toward and from the respective poles. A hammer *f*, attached to the armature, co-operates with the usual double arrangement of gongs or bells *g g*. Attached to the back bar and 65 embracing the ends and one side of the core is the usual permanent or polarizing magnet *b*. Upon the leg or pole-piece *c'* is mounted a condenser *x*, which is formed as a roll or spiral embracing said pole-piece. Said condenser may be formed of a layer of metal foil 70 coated with paper, shellac, or any other suitable dielectric of sufficient resistance to properly insulate the successive convolutions of metal foil from each other and from the pole-piece *c'*. A conducting-wire *n* connects the outer terminal of the magnet-winding with the metal coating of the condenser, and the line-terminals of the ringer-circuit *m o* are 75 connected to coil *a* and the metallic frame of the ringer, respectively. The magnet-coil and the condenser are inclosed in a suitable protective covering to exclude dust and moisture, so that when assembled the apparatus 80 does not differ in size, form, or general appearance from the conventional bipolar ringer.

The operation of the above-described apparatus is as follows: An alternating or magneto current sent over the line enters coil *a* of 90 the electromagnet by way of lead *m* and passes thence through connector *n* to the condenser, charging the latter. Upon discharge of the condenser and reversal of the current in the circuit armature *e* is attracted by pole-piece *c'* by reason of the current reversal and the fact that the armature is permanently polarized, while the pole-pieces are alternately polarized in opposite directions by the 95 passage of the alternating current. The next 100 impulse over the line moves armature *e* into contact with pole-piece *c*. This cycle of operations is repeated for each complete alternating impulse on the line, causing the armature to vibrate and actuate the hammer 105 or clapper *f*. It is to be observed that the

condenser α breaks the circuit for direct currents on the line.

I shall designate the armature of my ringer as "disconnected for any electrical function from the other parts." By this I mean that the armature does not close or open any circuit and has no function other than the conversion of magnetic energy into mechanical motion and that again into sound through the gongs.

Having thus described my invention, what I claim is—

1. In a signaling apparatus for telephone instruments, a combined ringer and condenser comprising a frame, a yoke of magnetic material, a pair of elongated cores extending from the said yoke parallel to each other, an insulated wire winding or bobbin upon one core, in approximately cylindrical shape, insulated conducting-sheets rolled and compressed upon the other core to form a condenser also approximately cylindrical in shape and of substantially the same diameter as the said bobbin, a pivoted armature mechanically held in proximity to the free ends of the parallel cores and disconnected for any operative electrical function from the other parts, a clapper-rod and clapper adapted to be actuated through said armature, sounding means adjacent to said clapper, a line-circuit, a telephone receiver and transmitter connected to said circuit, and connections from the circuit to the combined ringer and condenser including the said coil or bobbin and the said condenser permanently in series with each other so that all current through the coil or bobbin must pass into said condenser, together with means for supplying periodic current to said circuit for signaling, and continuous current for the telephone-transmitter, substantially as described.
2. In telephone apparatus, a combined

ringer and condenser, a combined ringer and condenser comprising a frame, a yoke of magnetic material, a pair of elongated cores extending from the said yoke parallel to each other, an insulated wire coil or bobbin upon one core, in approximately cylindrical shape, insulated conducting-sheets rolled and compressed upon the other core to form a condenser also approximately cylindrical in shape and of substantially the same diameter as the said bobbin, a pivoted armature mechanically held in proximity to the free ends of the parallel cores and disconnected for any operative electrical function from the other parts, a clapper-rod and clapper adapted to be actuated through said armature, sounding means adjacent to said clapper, a line-circuit, a telephone receiver and transmitter connected to said circuit, and connections from the circuit to the combined ringer and condenser including the said coil or bobbin and the said condenser permanently in series with each other so that all current through the coil or bobbin must pass into said condenser, together with means for supplying periodic current to said circuit for signaling, and continuous current for the telephone-transmitter, substantially as described.

In testimony whereof I have signed my name to this specification in the presence of two subscribing witnesses.

CHARLES E. EGAN.
